UNITED STATES PATENT OFFICE.

HERBERT POWELL REES, OF EALING, LONDON, ENGLAND.

WIRELESS TELEGRAPHY AND TELEPHONE RECEIVING SET.

Application filed August 9, 1921. Serial No. 491,046.

(GRANTED UNDER THE PROVISIONS OF THE ACT OF MARCH 3, 1921, 41 STAT. L., 1313.)

To all whom it may concern:

Be it known that I, HERBERT PERCY POWELL REES, commonly known as HERBERT POWELL REES, a subject of the King of Great Britain, residing at 8 Grange Park, Ealing, in the county of London, England, have invented new and useful Improvements in Wireless Telegraphy and Telephone Receiving Sets (for which I have filed application 10 in Great Britain dated 5th January, 1920, Patent No. 158,455), of which the following is a specification.

This invention relates to wireless telegraphy and telephony receiving instruments, 15 and more particularly to a receiving set which is adapted to be tuned over a wide range of wave lengths.

One important object of the invention is to enable the receiving set to be made in a 20 compact form and of small weight and nevertheless to be adapted for tuning over the said range to waves of the maximum length now in use. The receiving instruments or sets may therefore be constructed 25 in a form suitable for aeroplanes, exploring expeditions and the like where small weight and compactness are important considerations, and they may also be constructed in a form suitable for experimental work in 30 places where space is restricted and portability is desired. The invention, however, is not confined to portable apparatus.

In receiving sets for long wave lengths, a considerable space has been occupied heretofore by the inductance coils, and their supports, and the apparatus has been consequently heavy. Various methods of winding coils, such as pile, basket and lattice winding, for the purpose of increasing the 40 inductance and therefore wave-length obtained by a given length of conductor over that obtained by the ordinary single-layer cylindrical winding have been designed, but these expedients did not produce a coil of 45 compact form and small weight, such as is provided by these present improvements.

According to the present invention, a receiving set in which a thermionic valve is to be used, comprises a coil or coils wound in 50 a so-called ring form so that the self-induction of such coil, or of each of the coils, is at, or as near as convenient to, the maximum which it is possible to attain with a conductor of given length, diameter and insulation

thickness. That is to say, a coil to be comprised in the receiving set must have an axial length which is short in relation to its mean diameter with the turns in a number of closely juxtaposed layers but not necessarily in any definite order. The normal damping effect of such a coil on electrical oscillations is nullified when the said coil is employed in combination with a thermionic valve or valves in such known relation that oscillations are regenerated and maintained in the circuits. 55

It has been known for many years that maximum inductance could be obtained with a given length of conductor of given diameter, and insulation thickness, by winding 70 the conductor in the form of a ring coil of certain dimensions. According to the Clerk-Maxwell formula, for example, maximum inductance is obtained, in the case of a coil the aggregate of turns of which are of 75 square cross section, when the axial length of the coil is approximately 10/37ths of its mean diameter.

By the employment of this form of coil, 80 that is to say a coil of short axial length relatively to the mean diameter with the turns in a plurality of layers, in combination with a thermionic valve, the desirable result is achieved that waves of great length can be received by a receiving set of quite 85 small weight and dimensions and that the relatively large self-capacity is no hindrance but rather an advantage in the reception of such long waves, inasmuch as it increases the wave length obtained with a given length 90 of conductor, without unduly flattening the tuning say from 2000 metres upwards. It is to be noted that for the purpose of obtaining good reception of signals on any wave length when employing coils of small 95 bulk and weight as aforesaid, the ring coils need not be of, or even approximate to, the dimensions conforming with the Clerk-Maxwell formula, as it is found, for example, that ring coils of much shorter axial length 100 than that which would be given by the said formula tune to much longer wave lengths for a given length of conductor and maintain their advantages of compactness, lightness and cheapness in comparison with coils 105 of the forms heretofore employed. It is to be further noted that such coils may be of any shape, that is to say the core of the

former may be circular, square, ovoid, oblong and so on, and of any desired thickness, but preferably such that the axial length of the completed coil is not greater than one third of the diameter of a circle whose circumference is equal to the mean length of the turns of the coil. If this axial length be exceeded, the tuning may be unduly flattened without compensating advantage being obtained in the slight gain, if any, as regards weight and cost for wavelength, which may be effected. The cross section of the aggregate of turns may also be circular, square, ovoid, oblong and so on. Such a coil may be bent to another desired shape after being in circular or other form. The flexibility of dimensions and shape of such coils is frequently of advantage when designing instruments to fit into a space limited in any or all of its dimensions and constitutes an additional advantage possessed by such coils over other forms of coils.

In a receiving set for tuning over a very wide range of wave lengths the inductance coils may be divided into two independent sets, and if desired, a third set may be provided for use in tuning to the shorter wave lengths in the winding of which the axial length may be as short or even shorter than $3/37$ ths of the mean diameter and the insulation thickness of the conductor wire may be increased, by these means the self capacity is kept low while maintaining the inductance at a high figure in comparison with other forms of coil hitherto in use.

For the reception of the shorter wave lengths, it is sometimes advantageous not to couple the reaction coil with turns of the inductance coil in the aerial portion of the grid circuit but, instead, to couple it with inductance turns in a circuit connected with the aerial portion of the grid circuit.

A coil comprised in such combination may be sub-divided by tapping at required points, and this may be done during the winding by drawing out a loop at each of the said points and continuing the winding uninterruptedly from each of the said points. The coils aforesaid may be not only inductance coils in the aerial or grid circuit or in both but also the reaction coil or coils in the plate circuit.

In addition to the advantage of adaptability of the said coils of small bulk and weight for the reception of waves of any length, there is also the advantage that they can be wound very cheaply. It is only necessary to wind the required number of turns upon a rotating former without any particular degree of care or skill, as it is immaterial whether or not the turns are wound in regular layers. Coils so wound may be removed from the former and bound, waxed or varnished to keep the turns in place, thus con-

stituting a self supporting coil of high inductance, compact form and extreme lightness of weight.

In receiving sets, and particularly those designed to deal with a wide range of wave lengths, a difficulty is commonly experienced, when the inductance tuning switch is in some of the intermediate positions, due to interference with the tuned circuit by the overhanging part of the inductance. This overhanging part is that part which is not, for the time being, included in the tuned circuit. Owing to this peculiar interference, there are certain points, known as "slip points" where the continuity of the wave length curve on which oscillation is obtainable is broken so that oscillation on certain wave lengths is unobtainable. Means are provided in accordance with these improvements for avoiding this interference. For example, the aerial tuning switch may be adapted so that when it makes contact with a stud at one of these points, it also depresses an insulated stud or plunger, which opens a contact for cutting off entirely the overhanging part of the aerial inductance. However, owing to electrostatic interference, this expedient is not always effective. Alternatively, therefore, the switch arm may be furnished with a second contact adapted for making contact with a second set of studs, so that at the critical points, one or more sections of the overhanging part of the aerial inductance is or are short-circuited and therefore thrown out of resonance.

The annexed drawing, forming part of this specification, illustrates examples of receiving sets embodying the present improvements, and therein:

Figure 1 is a diagrammatic plan of one construction of apparatus in which the whole of the apparatus is enclosed in a single box.

Figure 2 is a diagram of the circuits and connections of the apparatus seen in Figure 1.

Figure 3 is a diagrammatic plan of a modified construction in which the apparatus is enclosed in three separate boxes A^1 , A^2 and A^3 .

Figures 4, 5 and 6 are diagrams of the circuits and connections of the apparatus seen in Figure 3 as arranged for the reception of short, medium and long waves respectively.

Figure 7 is a plan of an inductance switch fitted with auxiliary means for short-circuiting the overhanging portion of the aerial inductance, and

Figure 8 is a sectional diagrammatic view of an inductance switch having one of its studs fitted with auxiliary means for cutting off the overhanging portion of the aerial inductance.

Referring to Figures 1 and 2, B , B^1 and

B^2 are inductance coils wound in accordance with the essential feature of the present improvements, that is to say these coils are of ring form as is shown by the sectional views 5 of the coils B , B^1 , C , B^2 and C^1 . These coils are shown removed from the box A for the sake of clearness. C and C^1 are the reaction coils, which are preferably similarly wound in the so-called ring form and are 10 coupled in a variable manner with the coils B^1 and B^2 respectively. For example, and as shown in Figure 1, the coils C , C^1 may be slidably adjustable on the coils B^1 , B^2 , suitable finger rods C^{10} being connected with 15 these coils and extending to the exterior of the box for this purpose. Alternatively, however, the coils C , C^1 may be rotatably adjustable in relation to the coils B^1 and B^2 in known manner. D is a switch adjustable 20 over a set of contacts d , of which twelve are shown numbered from 1 to 12 respectively, these contacts being connected to tappings of the inductance coils B , B^1 and B^2 in the manner indicated by the corresponding 25 numbers on the connections from these coils. The tappings 1 to 3 and 5 to 8 are formed by drawing out loops from the conductor as it is wound to form the coils.

E is a three-pole two-way switch connecting up either of the reaction coils C and C^1 and either of the inductance coils B^1 and B^2 according to the wave length to be received. The coils B are additional inductance coils, 30 in series with the coil B^1 . F is a two-way switch connecting up the apparatus to a variable condenser G which, by means of the said switch F , may be placed in parallel with the tuning inductance, as seen in Figure 2, or may be placed in series with the 35 said inductance by reversing the switch F . H is a thermionic valve having three electrodes in the example shown, the heating cells being marked h and connected to the filament h^1 . J is a telephone receiver in 40 the high tension battery circuit K with condenser shunt k .

In the particular arrangement illustrated, the reaction coil C^1 , adjustably coupled with the inductance coil B^2 , is used for short 45 waves only and for this purpose the switch E is moved over to the left in Figure 1, thereby cutting out the coils B , B^1 and C , and the switch D is moved over on to any one of the contact studs 1, 2, 3 or 4 according 50 to whether a part only of the coil B^2 or the whole of this coil is to be placed in circuit. The four studs allow of four different inductance values for the coil B^2 according to the wave length to be received. 55 In this position of the switch E , the inductance B^2 is placed in the aerial circuit and is connected to the grid h^2 of the valve H , while the reaction coil C^1 is connected up to the electrode h^3 of the valve H and to the 60 telephone circuit.

For waves of medium length, the inductance coil B^1 is brought into circuit by moving over the switch E into the position shown in the diagrams and by moving the switch D at the same time on to any one of the studs 5 to 9, the inductance coil B^1 being correspondingly divided by tappings as shown in Figure 1.

The general arrangement of the circuits is the same as that already described for the 75 short wave reception, excepting that the coils B^1 and C are now brought into circuit in place of the coils B^2 and C^1 , as seen in Figure 2. To provide for a convenient factor of coupling of the plate circuit with 80 the grid circuit, however, the coil C may also be tapped at one or more points, and in the arrangement shown a single tapping is provided under the control of the switch L , which may place in the circuit either a 85 part or the whole of the coil C , according to its position on one or other of the studs 7. The switch arm L is connected to the right hand stud of the switch E .

Referring to the diagrammatic plan, Figure 1, the terminals j are connected up to the telephone receiver J shown in Figure 2, and the terminals k^1 are connected up to the high tension battery K , while the terminals h^4 belong to the low tension battery 95 h of the valve. The aerial N is connected to the terminal n , while the terminal o is connected to the earth O .

The circuit for long wave reception is substantially the same as that already described, but the switch D is moved over on to one or other of the studs d 10 to 12, bringing in one, or more of the inductance coils B . Three such coils are shown in Figure 1, but of course, the number may be varied and the inductance of the coils may progressively increase. Instead of a number of coils B , a single large coil may be employed tapped at different points, but it is usually more convenient to employ a series of coils of the type already described.

In order to prevent the interference of the overhanging portion of the inductance coils B at the slip points aforesaid, and so that the continuity of the wave length curve is ensured, a second set of studs d^1 may be provided concentric with the set d , the switch arm D making contact with studs of both sets. If the studs at the positions 7 and 8 are the critical studs, the corresponding studs in the set d^1 are connected by the connection d^2 with, for example, the stud at 11 in the set d . Therefore, when the switch arm D is adjusted to either the stud 7 or the stud 8, a portion of the inductance coils B , B^1 , that is to say that portion lying between the studs 7 or 8 and 11, is short-circuited by the connection d^2 , stud in the set d^1 and the arm D . If desired, and as shown in Figure 7, the whole of the overhanging

portion of the inductance coils B, in any position of the switch arm D, between studs 4 and 12, may be short-circuited by connecting the end stud at 12 of the set d with the 5 switch arm D as by the connection d³. The permanent connection of coils B and B¹ to the earth thus made, does not affect the reception of signals on the short wave lengths. Or, as shown in Figure 8, the stud at a critical 10 position may consist of a hollow cylindrical part d²⁰ encircling a plunger d²¹ of insulating material, the said plunger resting upon a spring contact blade d²², which normally makes contact with the bottom of the hollow stud part d²⁰. If the hollow stud part d²⁰ and the spring blade d²² be connected up as terminals of two successive sections 15 of a coil, it follows that when the switch arm D is depressed on to the hollow stud part d²⁰, it will depress the plunger d²¹ and the spring blade d²², thereby breaking the connection between the successive sections aforesaid. By one or other of these arrangements, the unutilized portion of the 20 aerial inductance is thrown out of resonance so that it does not interfere with the tuned aerial circuit.

It is to be understood that, while a particular type of circuit has been described 25 for purposes of illustration, the invention is not restricted to that type but may, for example, be also applied to a coupled aerial circuit instead of the plain aerial circuit shown in the diagrams in Figures 2, 4, 5 and 30 6 or to circuits in which both grid and plate circuits are tuned, or in which only the latter is tuned.

In the modification of the apparatus illustrated by Figures 3 to 6, the various parts 35 are contained in three separate compartments or boxes A¹, A² and A³, the coils in these boxes being connected up in different ways for the reception of short, medium and long waves, as will be described.

The box A¹ contains a sectional inductance coil B³ and a sectional reaction coil C², which can be variably coupled therewith, as by making it rotatably adjustable, as indicated in Figure 3. These coils B³, C², correspond respectively with the coils B¹ and C of Figure 1. The desired number of sections of the coil B³ is brought into the receiving circuit by the switch arm D¹ moving over the contact studs d⁴, the latter being numbered 1 to 8 corresponding with the eight tappings of the coil B³. The coil C² has one tapping giving two sections, one or both of which can be brought into circuit 50 by the switch L¹. The box A¹ is provided with terminals h⁴, j and k¹ corresponding to the similarly marked terminals in Figure 1, and also with a terminal n connected to the aerial N. It is further provided with terminals a¹ a² adapted to be connected to 55 corresponding terminals a³, a⁴ belonging to

the second box A², the terminal n also being connected to a terminal n¹ belonging to the second box which contains a three-pole three-way switch E¹. The connecting up of the various coils for short, medium or long wave length reception is accomplished by adjusting the switch E¹ to an appropriate 70 position as will be described.

The box A² contains a series of coils B⁴, five of which are shown, corresponding to the inductance coils B of Figure 1, and a switch D² moves over contacts d⁵ marked 0 to 6 for bringing into circuit the desired number of the coils B⁴, these coils being cut out entirely when the switch arm D² is on the contact marked 0. The switch arm D² also moves over a second set of studs d¹ some of which are connected by connections d² with certain of the studs d⁵ in a manner somewhat different from that described in 80 connection with the studs d d¹ in Figure 1, as will be hereinafter explained.

The box A³ contains a small inductance coil B⁵ divided into a series of six windings in the example shown. The inductance coil B⁵ may be wound in the ordinary manner, that is, as a single layer on a tube within which may be fitted the usual variable tuning condenser. The switch D³ is moved over the contact studs d⁶ marked 0 to 6, in order to bring into circuit the desired number of windings to suit the wave length to be received and to cut out the windings entirely when moved on to the contact 0. The box A³ may contain the condenser G between the terminals n³ (connected across to the terminals n² of the box A²) and a⁶ (connected to the terminal a⁵ of the box A² and to the earth 0 as shown).

Assuming that a short wave reception is desired, the switch E¹ is put over to the left to the position seen in Figure 3. The circuits thus completed will be seen clearly by reference to Figure 4. The aerial N is connected up to the end of the inductance B³ through the terminals n, n¹ middle arm of the switch E¹ and terminals a⁷, a⁸, the aerial oscillatory circuit continuing through a part or the whole of the inductance B³, the switch D³, and the condenser G to earth. The switch D¹ of the box A¹ should preferably be placed on stud 5, to place a portion of the inductance B³ in the grid circuit as seen in Figure 4, and in this case the connection between a² and a⁴ may be broken, also as seen in Figure 4. In this circuit, it will be seen that the reaction coil C² is not coupled with an inductance coil in the aerial circuit, but with the inductance coil B³, which is in the grid circuit, which is found to be advantageous for the reception of short wave lengths.

For medium wave lengths, the switch E¹ is turned to its middle position and an aerial oscillatory circuit is created, which 130

is represented by the diagram in Figure 5. The inductance B^5 is not now in use, but an appropriate number of sections of the inductance B^3 is put into the aerial circuit by 5 the switch D^1 , the connection between a^2 and a^4 being then closed as shown. The circuit from the aerial N is as follows: through terminals n , n^1 , first or left hand arm of switch E^1 , terminals n^2 , n^3 , switch D^3 10 (placed on stud 0) terminals a^8 , a^7 , middle arm of switch E^1 and terminals a^3 , a^1 , the circuit then continuing through the inductance B^3 , switch arm D^1 and terminals a^2 , a^4 , a^5 , a^6 to earth. 15 For long wave reception, the switch E^1 is moved over to the right thereby producing the circuit connections represented by the diagram Figure 6. The switch arm D^3 also may be placed over to the right, thereby 20 putting into circuit the whole of the coils B^5 . From the aerial N , the circuit is through the terminals n , n^1 , first arm of switch E^1 , terminals n^2 , n^3 , switch arm D^3 , inductance B^5 , terminals a^8 , a^7 , middle arm 25 of switch E^1 , an appropriate number of sections of the inductance B^4 , through the switch arm D^2 , which is set for connecting up the desired number of sections, through the third arm of the switch E^1 , terminals a^3 , a^1 , through a part or whole of the inductance B^3 , through switch arm D^1 and terminals a^2 , a^4 , a^5 , a^6 , to earth. 30

It will be seen from Figure 3 that there are five coils B^4 and seven studs in the sets 35 d^5 and d^1 numbered "0" to "6", the studs "2" and "3" in the set d^5 being connected together so that they are both terminals of the second of the coils B^4 . It will be seen further, that the mode of cross connecting 40 studs in the series d^1 and d^5 is as follows:— The No. "1" stud in the set d^1 is connected with the connected Nos. "2" and "3" studs in the set d^5 . Therefore, when the arm D^2 is on the No. "1" studs, that coil at B^4 which 45 is between "0" and "1" is cut in and the coil between "1" and "2" is short-circuited by the connection d^2 . This avoids a "slip point" which would otherwise occur during the tuning upwards in the wave-length 50 range by means of the condenser G . When the arm D^2 is on the No. "2" studs, the coils between studs "0" and "2" are cut in and the coils between "2" and "4" are short-circuited. Now the stud "3" in the set d^5 55 is the terminal of the same inductance coil at B^4 as the stud "2", so that when the arm D^2 is put on the No. "3" studs the coils between studs "0" and "2" are cut in but no short-circuiting of another coil occurs, as 60 is the case when the arm D^2 is on the studs No. "2".

It is to be understood that the invention is not limited to the practical examples herein described with reference to the drawings, 65 but that various changes and modifications

can be made without departing from the essential features as herein stated and defined by the claims.

I claim:

1. Radio receiving set comprising in combination an antenna tuning coil comprising a plurality of layers, each layer consisting of a plurality of substantially plane turns, the axial length of said coil being short in relation to its mean diameter, a holder for a three electrode vacuum tube, connections to said holder forming a grid circuit and connections to said holder forming an anode circuit reactively coupled with said grid circuit. 70

2. Radio receiving set for use with a three electrode vacuum tube comprising in combination an antenna tuning coil having an axial length which is short in relation to its mean diameter, the turns of said coil being in a plurality of layers, each consisting of a plurality of substantially plane turns, connections forming a grid circuit for the vacuum tube and connections forming an anode circuit for the vacuum tube reactively coupled with said grid circuit. 85

3. Radio receiving set comprising in combination an antenna tuning coil having an axial length which is short in relation to its mean diameter, the turns of said coil being in a plurality of layers, each consisting of a plurality of substantially plane turns, a three electrode vacuum tube holder, anode grid and cathode terminals mounted in said holder, connections between said grid terminal and said cathode terminals forming a grid circuit for the three-electrode vacuum tube, connections between said anode terminal and said cathode terminals forming an anode circuit for said vacuum tube and a reaction coil in said anode circuit coupled with said antenna tuning coil. 95

4. Radio receiving set comprising in combination, an antenna tuning coil having an axial length which is short in relation to its mean diameter, the turns of said coil being in a plurality of layers, each layer consisting of a plurality of substantially plane turns, a three-electrode vacuum tube holder, a three electrode vacuum tube supported in 110 said holder, connections between the grid and cathode of said tube forming a grid circuit, connections between the anode and cathode of said tube forming an anode circuit and a reaction coil coupled with said antenna tuning coil and connected in said anode circuit, said reaction coil having an axial length which is short in relation to its mean diameter and being composed of a plurality of closely juxtaposed layers, each layer consisting of a plurality of substantially plane turns. 115

5. Radio receiving set comprising in combination, an antenna tuning coil having an axial length which is short in relation to its 120 125 130

mean diameter, the turns of said coil being in a plurality of layers, each layer consisting of a plurality of substantially plane turns, a three-electrode vacuum tube holder, a three-electrode vacuum tube supported in said holder, connections between the grid and cathode of said tube forming a grid circuit, connections between the anode and cathode of said tube forming an anode circuit and a reaction coil connected in said anode circuit and movably mounted relatively to said antenna tuning coil to enable the coupling therebetween variable, said reaction coil having an axial length which is short in relation to its mean diameter and being composed of a plurality of closely juxtaposed layers, each layer consisting of a plurality of substantially plane turns.

6. Radio receiving set comprising in combination, connections forming an antenna circuit, a three electrode vacuum tube, connections forming a grid circuit for said tube, connections forming an anode circuit for said tube, a connection for impressing potentials upon the grid of said tube in accordance with oscillations in said antenna circuit, an inductance coil of ring form composed of a plurality of layers, each layer con-

sisting of a plurality of turns, a switching device adapted to connect said coil alternately in said antenna circuit or in the grid circuit of said tube and a reaction coil included in the anode circuit of said tube and coupled with the said coil.

7. Radio receiving set comprising in combination an antenna tuning coil having its axial length short in relation to its mean diameter and consisting of a plurality of layers, each layer consisting of a plurality of substantially plane turns, said coil having a plurality of taps, a three electrode vacuum tube, grid and anode circuits connecting respectively the grid and cathode of said tube and the anode and cathode of said tube, a reaction coil included in said anode circuit and variably coupled with said antenna tuning coil, a switching device for connecting any desired tap of said antenna tuning coil to the antenna circuit and an auxiliary switching device operatively connected with said first-named switching device for short-circuiting the portion of the antenna tuning coil not connected in said antenna circuit when said first-named switching device is placed in one of its operative positions.

H. POWELL REES.
